UNITED STATES PATENT OFFICE.

HARRY FERDINAND LEISSNER, OF LJUSNE, SWEDEN.

SPRING DEVICE.

1,260,921.

Specification of Letters Patent. Patented Mar. 26, 1918.

Application filed June 29, 1916. Serial No. 106,722.

To all whom it may concern:

Be it known that I, HARRY FERDINAND LEISSNER, a citizen of the Kingdom of Sweden, residing at Ljusne, Sweden, have invented new and useful Improvements in Spring Devices, of which the following is a specification.

This invention relates to speed regulating devices and more particularly to regulating devices operating by the aid of a centrifugal governor adapted to be adjusted for various speeds, while working.

Various constructions have been proposed in order to bring about such a regulating device. In certain cases a spring loaded centrifugal governor has been used, the spring of which is compressed more or less according to the speed desired. The intermediate members necessary for the transmission of power from said spring to the fly-balls have, however, rendered the construction of the governor too complicated, and owing thereto the use of such regulating devices is rather limited.

An object of this invention is the provision of a regulating device operating by means of a centrifugal governor which is provided with a simple device adapted to be applied to common governors without necessitating any change of their mechanism and to effect the adjustment of the regulating device for various speeds, while working.

Another object is to provide a regulating device of the above stated type having a spring member consisting of two or more springs of different strength, each of said springs operating within its separate range of speed.

A preferred embodiment of a regulating device constructed according to this invention is illustrated in the accompanying drawing, in which—

Figure 1 is a diagrammatic representation of the centrifugal governor provided with springs of the above named kind and of the connections between the governor and the member to be controlled. Fig. 2 is a sectional view of a spring device actuating the fly-balls of the governor and having two springs.

Referring to Fig. 2, the spring device comprises a helical spring 1 provided at the one end with a hook 2, by means of which the spring may be attached to one fly-ball 12 of a centrifugal governor. At the other

end the spring 1 is screwed onto a cylindrical member 3 having outer threads at the one end and formed at the other end as a sleeve 4 closed by a cover 5. Placed in the center of the cover 5 is a recess into which the end of the hook 2 is generally inserted. On account thereof, the tension of the spring 1 may be adjusted by turning the member 3 in relation to the spring. Located inside the sleeve 4 is another spring 6 of less strength than the spring 1 and bearing, at the one end, against the bottom of the sleeve 4 and, at the other end, against a nut 7 formed as a piston and adapted to move in the sleeve 4. Screwed into the nut 7 is a rod 8, which may be connected with the governor sleeve 13 movable along the governor shaft 13. The nut 7 is provided with a pin 9 secured to the same and entering a longitudinal slot 10 in the sleeve 4, so that the nut is prevented from turning, but is able to move in the sleeve on turning the rod 8. Secured between the bottom of the sleeve 4 and the nut 7 is a tube 11 surrounding the rod 8 and serving to limit the compression of the spring 6. The length of the tube 11 in relation to the strength of the springs 1 and 6 is so chosen, that on pulling, at the one side, at the hook 2 and, at the other side, at the rod 8 the spring 1 cannot be extended, ere the nut 7 bears against the tube 11.

As will appear from Fig. 1, such a spring device is provided between each fly-ball 12 and the movable governor sleeve 13. By turning the member 3 of each spring device the tension of the corresponding spring 1 is so adjusted, that it corresponds to the maximal speed desired of the machine in question and by screwing the rod 8 outward or inward the tension of the spring 6 is so adjusted, that it corresponds to the minimal speed desired of the machine.

The connection between the governor and the member to be controlled may for instance, be effected in the manner shown diagrammatically in Fig. 1. The governor sleeve 13 is by means of links 14, 15, 16 connected with said member. In the present case this member is supposed to be a main supply valve, the quite closed position of which is indicated by the line A, while the quite open position of the valve is indicated by the line B. The path of movement of the valve is indicated by the vertical line C. The link 15 is at the center connected with

a hand lever 17 pivotally mounted on the stationary shaft 18. In Fig. 1 three different positions of the fly-balls and of the hand lever are shown. Said positions are indicated by I, II, and III. Concerning the fly-balls, I designates their lowest position, II their highest position at the minimal speed of the machine, and III their highest position at the maximal speed of the machine. As to the hand lever 17, the position I corresponds to the stop position of the machine, the position II corresponds to the running of the machine at the lowest speed, and III to its running at the highest speed.

15 The device operates as follows: When the hand lever 17 is in the stop position I, the link-system 14-16 occupies the position designated by I, the fly-balls are in their lowest position I, and the supply valve is in its closed position B. If the hand lever be moved to the position II, this will have no influence on the fly-balls, and therefore the link 14 will remain in its position I, whereas the links 15 and 16 are moved to the position II^a. Owing thereto, the valve is fully opened, and the machine is started. According as the speed increases, the fly-balls 12 are raised, while the spring 6 is compressed. At the same time the link-system 14-16 is turned around the center II of the link 15 in such a manner, that the supply valve closes successively, according as the fly-balls are raised. When the fly-balls reach the position II, the link-system occupies the position II^b in which the supply valve is closed. Thus the supply may vary between a quite open and a closed position, while the fly-balls are moving between the positions I and II. In the position II of the fly-balls the spring 6 is compressed to such an extent, that the nut 7 bears against the tube 11.

40 If the greater speed is to be used, the hand lever 17 is reversed to the position III. At the beginning the fly-balls cannot pass the position II, and therefore the link-system occupies, after the reversal, the position III^a, in which the supply valve is quite open. This position is maintained, until the speed 45 of the machine is increased to such an extent, that the tension of the spring 1 is exceeded by the fly-balls. If the speed be further increased and the fly-balls begin to raise while extending the spring 1, the sup-

ply valve will be throttled successively, since 55 the link-system 14-16 is turned about the center III of the link 15. When the fly-balls 12 reach the highest position III, the link-system 14-16 occupies the position III^b in which the supply valve is closed entirely. 60 Thus the supply may vary between the fully open and the closed position, while the fly-balls are moving between the positions II and III.

Obviously, the number of springs operating consecutively may be chosen at will greater than two in correspondence to the number of different speeds of the machine for which the governor is to be adjusted. The different springs need not be placed one 70 inside another, as in the drawing, but may be located on a line or beside another, though the disposal described above, as saving room, is to be preferred.

Having now described my invention, what 75 I claim as new and desire to secure by Letters Patent is:

1. A spring device comprising an outer sleeve, an exterior spring secured on said sleeve and adapted for connection with an 80 element to be regulated, a sleeve in the first-named sleeve and held against endwise movement, a rod extending through the last-named sleeve and the end of the first-named sleeve and adapted for connection with a governor, 85 means on said rod to bring up against the last-named sleeve, and a spring surrounding said sleeve and interposed between said means and the end of the first-named sleeve.

2. A spring device comprising a sleeve exteriorly grooved adjacent to one end, a coiled spring surrounding said sleeve and having whirls adjacent to one end seated in said groove and adapted at its opposite end 90 for connection with a member to be regulated, a rod movable in the sleeve and adapted for connection with a governor and having means movable in the first-named sleeve, a sleeve surrounding said rod and interposed between said means and the end 100 of the first-named sleeve and a spring surrounding said sleeve between the means on the rod and the end of the first-named sleeve and arranged in the first-named sleeve.

In testimony whereof I have signed my 105 name.

HARRY FERDINAND LEISSNER.
